UNITED STATES PATENT OFFICE.

WILLIAM GARFIELD SHELDON, OF LONDON, ENGLAND, ASSIGNOR TO REMINGTON TYPEWRITER COMPANY, OF ILION, NEW YORK, A CORPORATION OF NEW YORK.

TYPE-WRITING MACHINE.

1,156,437.

Specification of Letters Patent. Patented Oct. 12, 1915.

Application filed July 18, 1914. Serial No. 851,729.

To all whom it may concern:

Be it known that I, WILLIAM GARFIELD SHELDON, a citizen of the United States of America, resident of London, England, have invented certain new and useful Improvements in Type-Writing Machines, of which the following is a specification.

My present invention relates especially to paper feeding mechanism for typewriting machines and its general object is to provide new and improved mechanism of the character specified.

More specifically stated, the object of the invention is to provide improved means for actuating a tally strip, said means being associated with other paper feeding means for continuously feeding another sheet. Such continuous feeding means is of a character commonly termed a platen sweep; and in the present instance I provide for actuating the tally feed by the same operation which actuates the platen sweep, the two sets of feeding devices or mechanisms being so related and operatively connected that the operative connection may be dispensed with or thrown out of use readily whenever desired so that either the platen sweep or the tally feed may be actuated without affecting the other mechanism. The tally feed mechanism in the present construction is not affected by the usual platen line spacing means which is provided in addition to the platen sweep.

To the above and other ends which will hereinafter appear, my invention consists in the features of construction, arrangements of parts and combinations of devices hereinafter described and particularly pointed out in the claims.

My invention will be more particularly described in connection with the accompanying drawings which illustrate the preferred form of said invention applied to the carriage of a No. 10 Remington front-strike typewriting machine, and wherein—

Figure 1 is a fragmentary side elevation of the upper part of said machine showing my invention applied thereto; Fig. 2 is a fragmentary front elevation of the carriage of said machine; and Fig. 3 is a detail side elevation of certain of the tally feeding devices viewed from the left.

The main frame of the Remington machine comprises a top plate 1 above which are fixed grooved guide rails 2 that co-operate through anti-friction balls 3 with the

front and rear bars numbered respectively 4 and 5 of a rectangular carriage truck which further comprises end bars 6. Shiftably connected with the truck through connections including devices 7 and 8 is a platen frame comprising end bars 9 and 10 which are rigidly connected by a cross bar 11 and a cross rod 12. Journaled on said end bars 9 and 10 are short shafts or parts 13 constituting the axle of a rotary platen 14. Said platen comprises a sheath 14^a and a wooden core 14^b, the core extending substantially full length but the sheath being cut short so as to permit a shorter fixed section or platen 15 to be arranged at the right thereof. The platen or section 15 is designed to accommodate the tally strip and comprises a sheath 15^a and a metal core 15^b which surrounds the core 14^b. The core 15^b is connected by screw and nut devices 16 and 17 with a bar 18 which is comprised in a tally supporting frame, said frame further including an arm 19 integral with and extending rearward from the right-hand end of the bar 18 and detachably secured to the rod 12. The construction is such that the tally frame comprising the parts 18 and 19 is rigidly secured to the platen frame while the tally platen 15 is rigidly secured to said tally frame and through it to the platen frame. The platens 14 and 15 may be regarded as the sections of a divided platen which as a whole comprises both the rotary part 14 and the fixed part 15.

While I prefer in the present instance to employ the sheath 15^a as a striking surface or platen proper, it may, if desired, serve as a backing for a small, plate-like detachable striking surface as in my prior application Sr. No. 832,458; filed April 17th, 1914. The corresponding parts in the present application and in said prior application are preferably substantially alike and it is not deemed necessary to describe in any further detail the construction in this respect. The main platen 14 is provided with the usual paper feeding devices comprising front and rear feed or pressure rollers 20 and 21 which co-operate with said platen to advance the paper when the platen is turned. These rollers, however, terminate short of the fixed platen. Devices are provided for turning the platen 14, said devices including finger wheels secured to the parts or sections comprising the platen axle 13, only the right-

hand finger wheel 22 being shown. The usual step-by-step line spacing devices are also provided for said platen 14, said devices comprising a ratchet wheel 23 which is operatively connected with the platen 14, for example, by wood screws 23^a which screw into the ends of the wooden core 14^b as shown. The ratchet wheel 23 is arranged at the right-hand end of the platen 14 but 10 has no connection with it, said platen and said ratchet wheel being independent of each other. A roller detent (not disclosed) co-operates with the teeth of the ratchet wheel 23 which is adapted to be turned by hand operated pawl and ratchet devices 15 comprising a pawl 24 pivotally supported on an arm 25 which turns on the right-hand part or axle 13 as a center. Said pawl is connected by a link 26 with a bell crank 27 pivoted to the platen frame and connected 20 in turn by a link 28 with a crank arm 29 fixed to the rear end of a spring controlled rock shaft 30 which turns in a housing 31 fixed to the platen frame and terminates at 25 its forward end in a line spacing handle or finger piece 32 which may be actuated to operate the pawl 24 and cause the same to turn the ratchet wheel 23 and platen 14 step-by-step for ordinary line spacing.

30 In addition means are provided for turning the platen 14 and advancing the work sheet rapidly and continuously, said means being preferably platen sweeping mechanism substantially like that disclosed in the 35 patent to Briggs and Ford, No. 955,942, granted April 26, 1910 to which reference may be had for details of construction not herein disclosed. Some of the parts are differently arranged in the two constructions 40 but in essentials they are the same. Said platen sweeping mechanism comprises a segmental gear or toothed segment 33 provided with an arm 34 which terminates in a lateral finger piece 35. The toothed or gear 45 segment is arranged outside the right-hand end bar 6, and its operating arm is normally substantially upright. Said segment is rigidly secured to a stub shaft 36 which is journaled on an arm or bar 37 rigidly secured to the end bar 10 by screws 38. A helical spring 39 surrounds the journal of the gear segment 33 and is secured at one end to said segment while its opposite end is anchored to the arm 37, said spring 50 55 storing the segment to normal position after operation. Said segment constantly meshes with a pinion 40 which is adapted to turn on the right-hand axle part 13 and has rigidly connected with it an arm or plate 41 60 at the outer end of which is pivotally supported at 42 a spring pressed pawl 43 which is adapted to engage with the teeth of a ratchet wheel 44 that is rigidly secured to the axle 13. The pawl 43 houses a spring 65 (not shown) which surrounds its pivot and

tends constantly to press it into engagement with the ratchet wheel 44. Said pawl and ratchet are, however, normally separated, the pawl being held out by reason of its contact with a fixed lateral stop pin 45 70 which is secured to a plate or arm 46 that may bear on the axle 13 and at its upper end is connected by a screw 47 with the outer end of the stub shaft 36 into which said screw is threaded. The construction 75 is such that the outer end of the stub shaft is additionally supported by the plate 46 which is fixed by the screw 47. When the finger piece 35 is pulled forward to actuate the toothed segment or rack 33 the pinion 80 40 will be turned rearward, swinging the arm 41 rearward, causing the pawl 43 to move rearward and separate from the stop pin 45. Thereupon the pawl spring (not shown) will cause said pawl to engage with 85 the ratchet wheel 44 which in turn will act on the platen 14 to give said platen a corresponding turning movement. The extent of this continuous turning movement of the platen depends on the setting of adjustable 90 stop devices, said stop devices comprising a lateral stop pin 48 fixed to a ratchet wheel 49, which bears loosely on the platen axle 13 so that it may be turned freely thereon to adjust and variably locate the stop pin 95 48. The positions of said ratchet wheel and of said stop pin 48, however, are normally fixed by a pawl or detent member 50 which bears rotatably on the stop pin 45. Said pawl at its lower end is provided with a tooth 100 which engages the ratchet wheel 49 while the upper end of said pawl above its pivot bears normally against the front side of the head of the screw 47. The pawl is held in this position by a U-shaped spring plate 51 105 which is riveted or otherwise secured to the pawl and normally embraces the head of the screw 47, thus fixing the pawl and the ratchet 49. By pulling outward the rear arm of the spring plate 51, the locking 110 pawl 50 may be released, so that it may be thrown out of engagement with the ratchet wheel 49, enabling the ratchet wheel and stop 48 to be adjusted as desired.

115 In the position of the stop pin 48 shown in the drawings, the platen may be continuously rotated through a distance equal to nearly three-quarters of a turn before the parts will be arrested and temporarily locked to prevent overthrow by the engagement of the tail of the pawl 43 with the stop 48. On releasing the handle 35 the gear segment will be restored to normal position, this position being determined by the engagement of the pawl 43 with the 120 stop 45. This continuous advance or forward sweep of the platen 14 is useful among other things to advance a bill sheet initially 125 into the machine past the usual printed heading and into position to receive the first 130

line of writing. Preferably I make use of this operation also to advance automatically the tally sheet through a unit distance. The tally sheet in the present instance is mounted on carriers or spools which are supported on uprights 52 and 53 fixed to the ends of the frame bar 18. These spools and their appurtenances are preferably of the construction disclosed in my prior application aforesaid and need not be here described in any great detail. The delivery spool 54 is mounted on a shaft (not shown) which projects leftward from the upper end of the upright 52. The tally strip 55 is carried in roll form by said spool, the free end of said tally strip being drawn off at the rear of the spool and fed around the fixed tally platen 15 with which it is in register and led upward at the front side of said tally platen to the receiving spool, carrier, or roll holder. Said receiving spool comprises a core 56 and flanges 57 and 58 and is mounted on a shaft 59 which at the left bears in a socket piece or journal 60 fixed to the upright 53, while at the right said shaft bears in and projects outward beyond the upright 52. Normally the receiving spool is connected to turn with the shaft 59 by devices comprising a disk 61 provided with a lateral pin 61^a which engages in any one of a plurality of holes in the right-hand spool flange 57. Rigid with the disk 61 is a ratchet wheel 62, the parts 61, 62 being suitably fixed to the axle of the shaft 59. A spring 63 secured to the upright 52 engages with the ratchet wheel 62 and maintains the receiving spool in adjusted positions.

Means are provided for turning the shaft 59 step-by-step to turn the receiving spool 40 step-by-step and draw or advance the tally strip correspondingly over the fixed tally platen. Said means, constituting the tally feeding means or step-by-step advancing devices, comprise, a clearly shown more especially in Fig. 3, a ratchet wheel 64 fixed to the outer end portion of the shaft 59. Loosely embracing said ratchet wheel is a frame comprising end plates 65 and 66 and a connecting web 67, the end plates being 50 drilled so that they may bear loosely on the shaft 59. The end plate 66 terminates at its lower end in a lug or tail piece 68 and at its upper end in a finger piece or key 69. The frame comprising the end plates provides a 55 carrier for a pawl member 70 which is arranged between said plates above the ratchet wheel 64 and is provided with a pivot pin 71 which extends laterally from its sides and bears in the end plates 65 and 66. The pin 80 71 projects at the left outward beyond the plate 66, and wound around this projecting portion of the pin is one end of a wire spring 72 which is bent into a U so as to engage the pawl 70 behind a retaining lug 70^a thereon, 85 the other end of said spring being anchored

to the plate 65. Said spring constantly tends to press the pawl 70 into engagement with the ratchet wheel 64 and normally maintains the pawl in operative position. A wire spring 73 coiled around the shaft 59 at the left of the carrier 65-67 is hooked over the projecting end of the pin 71 and tends normally to maintain the carrier and the pawl 70 in a normal position which is determined by a stop 74 with which the back 75 edge of the plate 66 engages. Said stop is formed in the present instance by the laterally projecting portion of an arm or bracket 75 which is secured fixedly to the inner face of the bar 37. Said arm 75 is 80 perforated to permit the passage of the shaft 59 therethrough thus providing an end bearing for said shaft. The lower end of the spring 73 is secured in a small hole in the arm 75. By pulling forward on the finger piece 69 the pawl 70 may be caused to act on the ratchet wheel 64 to turn the shaft 59 and tally receiving spool and advance the tally strip. The extent of this turning movement is limited in the present instance by stop devices comprising the lug 68 and the back of the stop 74, said lug engaging with said stop to limit the forward swing of the carrier and the pawl 70. The movement of the pawl in the present instance advances the tally strip a distance measured by two of the teeth of the detent ratchet wheel 62.

In addition to the hand operation of the pawl 70 through the finger piece 69 above described, means are provided for actuating the pawl automatically from the platen sweep 33-35. Said means in the present instance comprise a spring plunger or pin 76 which is supported in a housing 77, said housing being in the form of a hollow cylinder or thimble which is suitably fixed to the inner face of the arm 34 and projects laterally inward therefrom. The pin 76 bears slidably at its left in the end or head of the 100 housing which is perforated for the purpose while at its right said pin bears in a hole in the arm 34. A spring 78 is coiled around the pin 76 within the housing and is hooked at one end over a cross pin 79 on said pin 76, 105 said spring tending constantly to move the pin 76 leftward and maintain its inner end in position to engage with the upper end portion 70^b of the pawl 70 when the platen sweep is operated. Normally the pin stands some distance behind the pawl, as appears from Fig. 1. At its right-hand end the pin 76 terminates outside of the arm 34 in a head 80 and just to the left of said head the pin is reduced in diameter to provide a circumferential groove 81 over which fits the lower end of a lever 82, said lever being slotted as indicated at 83 to fit into said groove. The spring 78 normally maintains the head 80 of the pin 76 pressing against the lower arm 110 115 120 125 130

of the lever 82 as shown in Fig. 2, thus limiting the leftward movement of the pin 76 and fixing the normal position of the lever 82 in respect to its carrier, the arm 34. Said lever is pivoted on a cross pin 84 which bridges a slot formed in a lug or projection 85 fixed to and extending laterally rightward from the arm 34. The lever is arranged in said slot and extends upward, terminating in a finger piece 82^a which is in proximity to the finger piece 35 and may be manipulated concurrently therewith by the same hand of the operator. Said finger piece normally stands away from the face of the arm 34 as shown in full lines in Fig. 2. By pressing in on the finger piece and moving it to the dotted line position as shown in said figure, where it is arrested by the arm 34, the spring 78 is overcome and the pin 76 withdrawn from register with the end 70^b of the pawl 70 as indicated by the dotted lines in Fig. 2, so that said pin cannot engage the end 70^b when the sweep is operated. When, however, the parts are in the normal or full line relationship shown in said figure, the pulling forward of the finger piece 35 not only actuates the platen sweep but brings the inner end of the pin 76 into engagement with the part 70^b of the pawl and causes said pin to actuate the pawl as the platen sweep is actuated just as said pawl would be actuated by operating the finger piece 69. During return movement of the platen sweep the end of the pin 76 will contact with the front of the end 70^b and swing the pawl 70 on its pivot far enough to permit said pin to move past, but without affecting the ratchet wheel 64. If it is desired to actuate the platen sweep without affecting an advance of the tally strip it is only necessary for the operator as he pulls forward on the finger piece 35, to maintain the finger piece 82^a pressed inward to the dotted line position, this operation of the finger piece 82^a affecting a disconnection of the operating connections between the platen sweep and tally feeding devices.

The construction, it will be understood, provides a convenient means of automatically advancing the tally strip each time a bill sheet is inserted and advanced continuously to writing position. The right-hand portion of such bill sheet will ordinarily be superimposed on the tally strip so that the writing of the total or other entry on the bill sheet will be duplicated on the tally strip through suitable inking devices such as are disclosed in my prior application before mentioned. Usually this will be the only entry made on the tally strip in connection with the bill sheet and the tally strip will remain quiescent during such typewriting as may be entered on the bill sheet prior to the writing of the total as well as of any writing which may be done on the bill sheet

subsequently. After the bill sheet is withdrawn, however, it is usually desired to advance the tally strip so as to position it suitably for the next total to be written and, as stated, this is preferably done when the fresh bill sheet is entered and advanced continuously to position to receive the first entry. However, should it be desired for any reason to advance the tally strip in between these continuous advance movements due to the operation of the platen sweep, this may be done by actuating the finger piece 69. Also if it be desired to continuously advance the bill sheet either to feed it rapidly out of the machine after it has been completely written or for any other purpose, this may be done without affecting the tally strip by pressing leftward on the finger piece 82^a prior to actuating the finger piece 35.

Other methods of actuating the novel devices embodying my present invention for various desirable purposes will suggest themselves to those skilled in the art, as will various changes which may be made without departing from my invention.

What I claim as new and desire to secure by Letters Patent, is:—

1. In a typewriting machine, the combination of a platen, tally sweep mechanism including a finger piece, tally feed mechanism, devices operative from said finger piece for actuating said tally feed mechanism, and means including a finger piece in juxtaposition to said first recited finger piece for controlling said devices.

2. In a typewriting machine, the combination of a platen, tally sweep mechanism including a finger piece, tally feed mechanism, devices operative from said finger piece for actuating said tally feed mechanism, and means concurrently operative with said finger piece for positioning said devices so that they will be inoperative.

3. In a typewriting machine, the combination of a platen, platen sweep mechanism including a finger piece, tally feed mechanism including a second finger piece, and operative connections between said mechanisms controlled by a third finger piece.

4. In a typewriting machine, the combination of a platen, platen sweep mechanism including a finger piece, tally feed mechanism including a second finger piece, and operative connections between said mechanisms controlled by a third finger piece, said first named finger piece and said third finger piece being concurrently operative.

5. In a typewriting machine, the combination of a platen, platen sweep mechanism including a finger piece, tally feed mechanism including a second finger piece, and operative connections between said mechanisms controlled by a third finger piece, said third finger piece being arranged in proximity to the first named finger piece and being op-

erative by the same hand that operates said first named finger piece and concurrently therewith.

6. In a typewriting machine, the combination of a rotary platen, hand controlled means for giving said platen a continuous turning movement, tally strip mechanism for advancing the tally feed independently of said platen, and means for operating said tally feed mechanism from said hand controlled means.

7. In a typewriting machine, the combination of a rotary platen, hand controlled rack and pinion mechanism including a finger piece for advancing said rotary platen continuously, and tally feed mechanism operative from a device supported by said finger piece.

8. In a typewriting machine, the combination of a rotary platen, platen sweep means for turning the same comprising a gear segment provided with an arm or extension terminating in a finger piece, tally feed mechanism, and a device on said arm for operating said tally feed mechanism.

9. In a typewriting machine, the combination of a rotary platen, platen sweep means for turning the same comprising a gear segment provided with an arm or extension terminating in a finger piece, tally feed mechanism, and a hand controlled spring pressed pin mounted on said arm and adapted to actuate said tally feed mechanism.

10. In a typewriting machine, the combination of a rotary platen, hand operated step-by-step line spacing devices for said platen, platen sweep mechanism for advancing said platen continuously, and tally feed mechanism independent of said line spacing mechanism but automatically operative by said platen sweep mechanism.

11. In a typewriting machine, the combination of a rotary platen, line spacing means for turning said platen step-by-step, other means for giving a continuous turning movement to said platen, and tally feed mechanism independent at all times of said step-by-step line spacing mechanism but adapted to be automatically operated when said means for continuously advancing the platen is actuated.

12. In a typewriting machine, the combination of a rotary platen, means for turning said platen continuously to advance a work sheet thereover into initial writing position, line spacing means for line spacing said platen step-by-step independently of the continuous turning means, and tally feed mechanism automatically operative by said continuous turning means.

13. In a typewriting machine, the combination of a rotary platen, means for giving a continuous turning movement thereto, adjustable stop devices for variably limiting

the extent of said continuous turning movement, tally feed mechanism, stop devices for limiting the extent of the tally feed, and connections between said tally feed mechanism and said means.

14. In a typewriting machine, the combination of a divided platen, means for advancing paper step-by-step over one section of said platen so as to space between the lines, other means for advancing said paper initially to position it for receiving the first line of writing, means for advancing a tally strip over another section of said platen to space between the lines, and operative connections between said tally advancing means and said means for advancing the paper initially.

15. In a typewriting machine, the combination of a divided platen, means for advancing paper step-by-step over one section of said platen so as to space between the lines, other means for advancing said paper initially to position it for receiving the first line of writing, means for advancing a tally strip over another section of said platen to space between the lines, and operative connections between said tally advancing means and said means for advancing the paper initially, said connections being rendered inoperative at will.

16. In a typewriting machine, the combination with a platen, and means for feeding a main sheet thereover; of tally feeding means comprising a rotary carrier, a shaft on which said carrier is mounted, a ratchet wheel fixed to said shaft, a pawl carrier loosely pivoted on said shaft, and a pawl pivoted on said pawl carrier; and means for turning said platen to feed the main sheet and for actuating said pawl carrier, said means comprising a spring controlled arm.

17. In a typewriting machine, the combination with a platen, and means for feeding a main sheet thereover; of tally feeding means comprising a rotary carrier, a shaft on which said carrier is mounted, a ratchet wheel fixed to said shaft, a pawl carrier loosely pivoted on said shaft, a pawl pivoted on said pawl carrier, stops for limiting the effective operation of said pawl, and a finger piece for actuating said pawl carrier at will; means for turning the platen to advance the main sheet continuously thereover, said means comprising a spring controlled arm; and a retractable spring plunger on said arm adapted to coöperate with said pawl carrier to actuate said pawl automatically.

18. In a typewriting machine, the combination of a platen, a platen sweep comprising a swinging arm, tally feed mechanism, and means for actuating said mechanism comprising a device mounted on said swinging arm.

19. In a typewriting machine, the com-

bination of a platen, a platen sweep comprising a swinging arm, tally feed mechanism, and means for actuating said mechanism comprising a spring plunger supported on said swinging arm.

20. In a typewriting machine, the combination of a platen, a platen sweep comprising an arm, tally feed mechanism, means for actuating said mechanism comprising a spring plunger supported on said arm, and a hand lever also mounted on said arm for retracting said plunger at will to inoperative position.

21. In a typewriting machine, the combination of a platen, a platen sweep comprising an arm, tally feed mechanism, and means for controlling said mechanism comprising a cylindrical housing fixed to said arm, a pin slidable in said housing, a spring constantly pressing said pin in one direction, and a hand lever pivoted to said arm and having a loose connection with said pin, said hand lever being operative to overcome said spring and retract said pin to inoperative position.

22. In a typewriting machine, the com-

bination of a platen, a platen sweep comprising an arm, tally feed mechanism, and means for controlling said mechanism comprising a cylindrical housing fixed to said arm, a pin slidable in said housing, a spring constantly pressing said pin in one direction, and a hand lever pivoted to said arm and having loose connection with said pin, said hand lever being operative to overcome said spring and retract said pin to inoperative position, said arm being provided with a finger piece, and the finger piece of said hand lever being arranged in proximity to the finger piece of said arm and being operative by the same hand that operates said first named finger piece and concurrently therewith.

In testimony whereof I have signed my name to this specification in the presence of two subscribing witnesses, this 15 day of July, 1914.

WILLIAM GARFIELD SHELDON.
